HOSIERY REPAIR APPARATUS

Luciano Argentin André, Mexico City, Mexico

Application June 25, 1952, Serial No. 295,510

2 Claims. (Cl. 66—1.5)

The present invention is related in general to mechanical apparatus, devices, or accessories, and especially to small machines for relooping runs in women's stockings, and refers more particularly to a novel, useful and very practical improved apparatus for relooping hosiery, which apparatus provides great and very appreciable advantages over similar apparatus used and known heretofore.

The small machines or apparatus for relooping the runs frequently occurring in fine ladies' stockings are well known, but said apparatus must be operated manually with a constant effort of the hand or, rather, of the wrist, so that after the operators have been working with them for a number of hours, the task becomes exhausting and frankly very painful. The improved apparatus of my invention tends to remedy this serious drawback, eliminating 75% of the work required of the operator and almost all the manual effort.

Briefly stated, the apparatus of the invention comprises a pneumatic pump adaptable to any sewing machine on the part to which the needle is secured and which has a vertical movement, said pump being provided with its corresponding ball valve and air regulator. Said pneumatic pump transmits compressed air through a flexible tube or conduit, especially of very flexible rubber, leading to another small pump to the piston of which is adapted a part for holding the needle which performs the relooping. Said piston is provided with a spring the resistance of which overcomes the piston thrust and with a similar smaller spring which acts as a shock absorber. Thus, as the sewing machine or any other mechanical drive transmits, by means of its mechanical movement, a reciprocating movement to the piston of the larger pneumatic pump, the latter in turn transmits movement to the smaller pump connected thereto, furnishing an up-and-down movement to its piston and accordingly to the needle secured to the end of said piston by means of an appropriate device, so that the operator need exert no effort whatsoever to push through the relooping needle and only has to guide said needle along the run to be repaired.

As will easily be understood, the present apparatus has two very important basic advantages: The first is that it can be adapted to any sewing machine to furnish the power and reciprocating movement required for operation of the needle; and the second is that there is provided an apparatus having an automatic movement which eliminates the effort which must be exerted by the hand in all similar apparatus used and known heretofore, thus simplifying to the minimum the operative work and relieving to a large extent the exhausting nature of the work performed by the operators during a day of work. Furthermore, it can be adapted to any type of machine with a minor change in the clamp bar, both to electric and pedal-operated sewing machines, without using any tool. Its performance is far more perfect than that of any of the manually operated machines used and known heretofore, in addition to which its efficiency is greater

and its output also is greater. They are appreciably more economical than the manual machines previously known and used, and far more simple to operate than said manual devices. The device of the invention is of a very small size and so light in weight that it can even be carried in a pocket.

These and other advantages, features and details of the automatic apparatus of my invention, together with features distinguishing it from known devices, will become clearly evident in the course of the following description as likewise in the drawings attached in illustration thereof, the same reference numbers having been used in said drawings to indicate the same parts in the five figures shown.

In said drawings:

Fig. 1 is a side elevation view of an automatic apparatus for relooping stockings, constructed in accordance with the invention.

Fig. 2 is a plan view and projection of the same apparatus illustrated in the preceding figure, the flexible conductor tube, uniting the two elements which substantially constitute said apparatus, being shown as cut.

Fig. 3 is a side elevation of the apparatus of the invention, similar to that shown in Fig. 1, but almost wholly in longitudinal section along each of its parts, for the purpose of illustrating the parts which form said apparatus and the internal arrangement thereof.

Fig. 4 is an elevational view of the piston and needle carrier of the smaller pump, guided by hand; and

Fig. 5 is likewise an elevational view of the part constituting the shock absorber of said piston.

Before describing in detail the improved apparatus for relooping hosiery, of my invention, I wish it to be clearly understood that the drawings illustrate only by way of example one of the preferred forms of carrying out the invention, without said invention being limited to the specific details illustrated in the drawings and described in the following specification or description. Recourse may therefore be had to such variations and modifications as may become or be considered necessary or convenient in practice, without departing from the principles and scope of the invention and within the scope of the claims annexed hereto. For example, it is obvious that the part serving as a support for the pneumatic pump may be varied or changed according to the type of sewing machine to which it be adapted or to the mechanical movement transmitted to its piston; likewise the control bar of the piston may be changed for the same reasons.

As illustrated in the attached drawings, the apparatus consists substantially of two principal elements united and connected by a small flexible tube, said elements being a pneumatic pump which transmits compressed air to another similar but smaller pump, with the looping needle adapted to the end of its piston. The pneumatic compressed-air pump comprises a metal tube 10, the approximate dimensions of which are, enunciatively and not restrictively, 25 mm. in diameter and 75 mm. in length, said metal tube constituting the body of the compressed air pump. At one of its ends (the lower as seen in the drawing), it is provided with a metal plug 11 (Figs. 1 and 3 of the drawings), in which there is adapted a ball valve 12, for the absorption of air, and a special screw 13 which acts as a jet for regulating the air pressure, so that if it is closed, either the maximum air pressure can be utilized or the escape of part of the pressure allowed to reduce the same, as will appear later. Near the lower edge of tube 10, as shown in Figs. 1 and 3 of the drawings, there is a small metallic tube 14, for the outlet of compressed air by means of piston 15 (Fig. 3) which moves tightly within tube 10 and is driven by rod 16. Said piston 15 is provided with and carries attached to its under surface a box-shaped packing 17, inside which

is fitted the perforated disc or washer 18. Packing 17 and washer 18 are adjusted to piston 15 by means of screw 19, as shown clearly in Fig. 3 of the drawings.

At the opposite end of tube 10 (the upper end in the drawings) is mounted annular attachment part 20, which is pressure-adjusted by means of screw 21 (Fig. 2). Said annular pressure part 20 has an extension 22, provided with bore 23, which is adjusted by means of screw 24. This extension 22 permits of connecting the apparatus wherever may be most convenient, but principally to a sewing machine as, for example, to the fixed bar on the front portion of a sewing machine.

The said piston 15 is operated, as aforesaid, by a small connecting rod 16, having ball-shaped ends 25 and 26. Ball 26 is lodged with some degree of clearance with respect to piston 15, said connecting rod 16 projecting through bore 27, whereas upper ball 25 is lodged in a small bar 28 (approximate dimension, 50 mm.) provided on its front end with a screw 29 having a bored head 30. This bar 28 can be adapted, by means of its screw 29—30, to the movable part of the sewing machine, that is to the part to which the needle is adapted, which moves vertically up and down. In this manner the sewing machine transmits a vertical up-and-down movement to bar 28, connecting-rod 16 and piston 15, for compressing the air inside tube 10, which air is fed or absorbed by means of ball valve 12 and expelled through tube 14. In other words, the sewing machine supplies to part 28, a vertical up-and-down movement which said part in turn transmits to connecting rod 16 and successively to piston 15, which functions to compress the air inside tube 10, absorbed by said tube during its upward stroke by means of valve 12, injecting this compressed air during its downstroke through tube 15 adapted to plug 11 and communicating with the inside of tube 10.

Tube 14 injects the compressed air, by means of flexible tube 30' (preferably of rubber), to the other device which completes this apparatus and is described below:

Said device, which completes the apparatus, of the invention, is the one which is guided by hand to reloop the damaged article, being held as one holds a pencil or like article, and consists of a part 31, generally quadrangular in section, provided with a longitudinal bore 32 centrically disposed and a similar bore 33 transversally disposed and connected to the former. This piece 31, which constitutes the head of the manual device, is provided at its end with a tube 34, connected to longitudinal bore 32, said tube projecting sufficiently to serve as a connection with flexible tube 30' already mentioned. Said tube 34 provides the pneumatic communication between the two devices forming the apparatus. On its opposite end, said head 31 has a threaded portion 35 (Fig. 3), to which is screwed a tube or tubular part 36, terminating in a conical shape, as clearly seen in Figs. 1 and 3 of the drawings. Inside this tubular part 36 is lodged a piston 37 (Fig. 4 of the drawings), likewise tubular and having a threaded portion on its front end, for receiving screw 38 which secures, together with washer 39, pressure packing 40. Around tubular piston 37 there is disposed a spiral spring 41, which acts as an antagonistic spring and the resistance of which overcomes the compressed air passing through tube 30' to push piston 37 outwardly, causing a certain portion thereof to project outside of tubular part 36.

Piston 37, which is displaced reciprocatorily or up and down inside said tubular part 36, is provided with slots 42 (Fig. 4) traversing it from side to side, which slots 42 limit the stroke of said piston 37.

Inside piston 37 which, as aforesaid, is tubular, is lodged a small cylinder 43 (Fig. 5), with a small bore 44 and a spring 45 at its end, said spring acting to damp the shock of the stroke of said piston. Crossing slots 42 and small bore 44 is a fine bolt or crosspiece 46, formed as clearly shown in Figs. 1 and 3 of the drawings, which small crosspiece 46 also passes into fine perforations made close to the conical end of tubular part 36.

At its outward end, piston 37 has a threaded portion 47 terminating in a conical tube 48 covered with a conical plug 49, which constitutes the needle-carrying device of the apparatus. To this needle-carrier 49 is adapted and secured any needle of those available on the market for relooping a stocking stitch article containing a run.

The air compressed by the pneumatic pump inside tube 10 is conducted by flexible tube 30' to the combination of parts above-described, which constitute the manual device of the present apparatus; so that upon covering with a finger the transversal bore 33 in head 31 of said device (which bore constitutes an air exhaust to stop operation of the device when not desired), said compressed air presses against small piston 37 which performs its reciprocatory movement with the cooperation of the antagonistic spring 41, said motion being transmitted to the needle adapted to needle-carrier 49, disposed at the end of said piston, whereby such motion allows of picking up the displaced stitches of the stocking or the like, restoring them to their original position.

The screw and washer 50, strategically disposed close to the edge of tube 10 and on the annular fastening piece 20 serve exclusively to avoid any undue displacement of plunger 15, the upper surface of which abuts said washer and screw 50.

Having thus described the invention, what I consider as new and desire to secure by Letters Patent is:

1. A relooping tool, comprising a tube provided at one end with an opening and at its opposite end with means having an inlet port for admission of pulsation of air under pressure and an exhaust port, a piston element 40 mounted in the tube and extending through the opening, said piston element carrying a packing at its lower end and a needle clamp at its upper end, a spring between the packing and a shoulder formed on the interior of the tube, means for limiting the reciprocable movement of the piston element and cushioning the shock including slots 43 in the piston element, a pin secured in the tube and extending through the slots, a plug mounted on the pin, and a spring in the piston element between a shoulder therein and the plug.

2. A relooping tool, as defined in claim 1, wherein the inlet port and the exit port are formed in a plug inserted in the tube, the exit port being open for application of the finger of the operator to control the movement of the piston element.
